UNITED STATES PATENT OFFICE.

PETER SANTURELLO, OF COLUMBUS, OHIO.

HEATING-IRON.

1,073,933.

Specification of Letters Patent. Patented Sept. 23, 1913.

Application filed August 15, 1912. Serial No. 715,213.

To all whom it may concern:

Be it known that I, PETER SANTURELLO, a citizen of the United States, residing at Columbus, in the county of Franklin and State of Ohio, have invented certain new and useful Improvements in Heating-Irons, of which the following is a specification.

My invention relates to the art of forming Marcel waves in hair and resides more particularly in the provision of a heating iron for this purpose. The true Marcel wave is in the nature of a compound undulation or series of undulations, compound in the sense that, besides being normally serpentine, the adjacent undulations are laterally disposed in relation to each other and in this manner are more than a simple zig-zag or purely serpentine formation. Further than this, all of these undulations must be of a smooth regular flowing nature. To attain the above, I have provided a heating iron which has all of its working surfaces of approximately cylindrical form and being so constructed that when the hair is wound about the same, all abrupt variations caused by having comparatively sharp corners, are eliminated. More specifically, I have found it desirable to have a plurality of prongs extending from both sides of a central stem, both the prongs and stem being of an approximately cylindrical formation. The effect gotten from a structure such as this is somewhat enhanced by arranging the prongs upon opposite sides of the central stem in staggered relation to each other. My heating iron also possesses other structural advantages which will be apparent from the following detailed description of the same.

The preferred embodiment of my invention is shown in the accompanying drawings, in which similar characters of reference designate corresponding parts, and in which:

Figure 1 is a top plan view of my improved heating iron, Fig. 2 is a side elevation thereof, Fig. 3 is a bottom plan view of my improved heating iron showing the slideable spring element for the retention of the free end of a lock of hair, Fig. 4 is a perspective view of my improved curling iron showing the manner in which the hair is to be wound thereon in order to attain the proper "Marcel" wave, Fig. 5 is a section taken on line 5-5 of Fig. 4 and like-

wise showing the lock of hair upon the heating iron and disclosing the convex central curve produced by the winding of the hair about the rod of the heating iron, and, Fig. 6 is a plan view of a lock of hair having the true "Marcel" wave, from which it will be seen that the normal undulations are laterally displaced in relation to each other.

In the drawings, my improvement is shown as comprising a handle element 1 into which lead electric wires 2 under the control of a switch 3 of any suitable form (details of switch not shown). The body of the heating iron is preferably formed of parts 4 and 5 superimposed upon each other and secured together by screws 6 and 7. These members 4 and 5 are of such form as to produce, when assembled, a central cylindrical stem or rod 8 and laterally extending substantially cylindrical prongs 9 and 10 disposed upon opposite sides of the stem and forming a staggered series of prongs about which the hair is to be wound in the manner shown in Fig. 4. For structural purposes, the upper element 4 preferably has its prongs provided with downwardly extending lips 11 and the lower element 5 has its prongs somewhat shorter so as to fit within the said lips 11. The interior of these prongs and of the central stem or rod is preferably cut out for the reception of heating coils as shown at 12.

Under normal conditions, it is desirable to provide the first two prongs of the body portion with retaining hooks 13 and 14 to prevent the lock of hair from slipping off, this being particularly liable to happen when the hair is being curled by a non-professional manipulator. The provision of these hooks 13 and 14 guards against this danger in operation by either a "left-handed" or "right-handed" operator. To further facilitate the use of my improved iron by a non-professional manipulator, I have provided a trackway 15 upon the lower face of the element 4 and a slideable spring 16 dove-tailed into said trackway and having a knurled piece of fiber 17 to facilitate sliding thereof without subjecting the operator to any discomfort due to the heated condition of the iron.

In operation, and directing attention to Fig. 4 of the drawings, the lock of hair will desirably be wound upon the body portion of the heating iron starting at or adjacent

to the handle. It will first be looped about the stem or rod of the body portion and will extend beneath the same over the side thereof, across the top thereof and down behind the first prong element, then underneath the prong element upwardly alongside the prong element and then reversed over the top of the stem and downwardly under the next prong element in a manner clearly apparent from this figure. It would seem from this that the true undulation, which may be described as the serpentine undulation, is produced by the passage of the lock of hair into contact with the prongs. The supplemental or lateral undulation which completes the compound curve is apparently effected by the passage of the lock of hair across the stem or rod of the body portion. This may or may not be true, for the reason that it is difficult to separate the effect of the different parts of this body portion. The essential fact, however, is that the winding of the lock of hair about the cylindrical body portion of the heating iron and the throwing in of the switch, will serve to heat the lock of hair in such a distorted position that there results a compound undulation known as the "Marcel" wave. As stated, one of the hooks 13 and 14 prevents the lock of hair from slipping off the inner end of the body portion and the spring element 16 may be readily adjusted to clamp the other end of the lock of hair upon the body portion.

What I claim, is:

1. A heating iron for use in forming Marcel waves comprising a central stem, and a plurality of prongs extending from both sides of said stem, said stem and said prongs being of approximately cylindrical formation.

2. A heating iron for use in forming Marcel waves comprising two main sections, said sections being each formed of a central stem and a plurality of prong sections extending from both sides of each of the stems in staggered relation, each of the said stems and prong sections being of approximately semi-cylindrical hollow formation, a handle, and electric heating means disposed in the hollow portions formed when the said sections are in superimposed position.

3. A heating iron for use in forming Marcel waves comprising a central stem, a plurality of prongs extending from both sides of said stem in staggered relation, said stem and said prongs being of substantially cylindrical formation, a handle, heating means, and guard members for preventing the hair from sliding off the ends of said prongs.

In testimony whereof I affix my signature in presence of two witnesses.

PETER SANTURELLO.
